PEDESTAL FOR CAR-TRUCKS.

1,118,908.

Specification of Letters Patent. Patented Nov. 24, 1914.

Application filed June 20, 1914. Serial No. 846,311.

To all whom it may concern:

Be it known that I, HARRY M. PFLAGER, a citizen of the United States, residing at St. Louis, Missouri, have invented a certain new and useful Improvement in Pedestals for Car-Trucks, of which the following is a full, clear, and exact description, such as will enable others skilled in the art to which it appertains to make and use the same, reference being had to the accompanying drawings, forming part of this specification, in which—

Figure 1 is a side elevational view of a pedestal of my improved construction with a portion of one of the horns or jaws in vertical section. Fig. 2 is a plan view of one of the pedestal horns or jaws. Fig. 3 is a horizontal section taken approximately on the line 3—3 of Fig. 1. Fig. 4 is a rear elevational view of one of my improved pedestal jaws or horns.

My invention relates to new and useful improvements in pedestals for passenger car trucks, the principal object of my invention being to generally improve upon and simplify the construction of the commonly used types of pedestals, and provide a construction wherein either one of the pedestal horns or jaws may be readily detached from the truck frame without disturbing the opposite or mating jaw, which arrangement not only greatly simplifies, but effects a material saving in time and labor in repairs, where either horn or jaw becomes broken or unfit for service.

To prevent excessive wear of the pedestal horns or jaws where they contact with the journal boxes, the inner faces and bearing ribs of the jaws are provided with hardened surfaces, and where the pedestal is made in a single piece as ordinarily constructed, it is a very difficult matter to grind the hardened surfaces on the inner faces of the jaws, which operation is necessary in finishing the pedestal jaws so as to insure a proper working fit. By making the jaws separate, the hardened metal surfaces which serve as bearing faces for the journal box can be readily ground and finished.

Heretofore it has been the general practice to form the pedestal in a single casting, substantially of inverted U-shape, said pedestal being attached to the wheel piece of

the truck by two vertical and three horizontal bolts.

Practically the only normal load that the pedestals are subjected to is produced by the application of the brakes to the car wheels and the pressure resulting from this load is transmitted through the wheels, axles, journal boxes and their parts to the inner faces of the pedestal jaws, and where the pedestal is made in a single piece, all of the attaching bolts act in a certain degree to resist the strains thus produced, and prevent the pedestal from being separated from the truck frame.

Where cars are involved in a wreck, it has been noted that the first parts of the truck to fail or break are generally the pedestals, and if one horn or jaw of a pedestal is broken, the entire pedestal has to be replaced, but where the pedestal horns or jaws are made separate as contemplated by my invention, either one may be readily replaced in case of breakage, without disturbing the mating horn or jaw.

My invention consists in certain novel features of construction and arrangement of parts, hereinafter more fully described and claimed.

As will be seen in the drawing, the jaws of my improved pedestal are separately formed and made in rights and lefts in order that they can be properly arranged in pairs on the wheel piece of the truck frame. Each horn or jaw comprises an outer wall 10 and an inner wall 11, and uniting the lower portions of these walls is a substantially L-shaped web 12. The horizontal leg 90 of this web 12 is provided with an aperture 13 which receives the bolt utilized in attaching the bit or tie bar which connects the lower ends of the pedestal jaws.

Formed integral with and connecting the upper outer portions of the walls 10 and 11 is a horizontally disposed web plate 14 which, when the pedestal is applied to the truck frame, bears directly against the underside of the wheel piece, and formed through this web plate is an aperture 15 which receives the vertical bolt that serves as a part of the pedestal attaching means. The outer plate 10 is provided at its upper end with an upwardly projecting extension 105 10* which lies against the outer face of the

wheel piece of the truck frame, and formed through this extension is a series of apertures 16 which receive the horizontally disposed bolts utilized in attaching the jaw to 5 the wheel piece of the truck frame.

Formed integral with the inner edges of the plates 10 and 11 are vertically disposed outwardly projecting bearing ribs or flanges 17, and the inner edges of said plates 10 and 10 and 11 and the outer faces of these flanges are hardened in any suitable manner to provide wear resisting surfaces for the journal 15 box which is positioned between the horns or jaws.

15 By forming the pedestal jaws or horns separate the grinding of the hardened surfaces is greatly facilitated and consequently said horns or jaws can be finished with the expenditure of comparatively little time and 20 labor.

In case either jaw or horn becomes broken or unfit for service, it can be readily removed and a new part substituted without detaching the companion jaw, thus effecting 25 a material saving in the cost of repairs.

In practice when the brakes are applied, force is applied to one of the pedestal jaws in the direction indicated by the arrow A in Fig. 1, which force tends to swing the 30 jaw upon the fulcrum point X, Fig. 1. Such action produces shearing stresses upon the horizontally disposed bolts which pass through the apertures 16, but, of course, these bolts are made amply large to take 35 care of said shearing stresses.

The lateral forces transmitted from the journal boxes to the pedestals are much smaller than those produced by brake application, and said lateral forces are readily 40 taken care of by the vertical bolt which passes through the aperture 15 in web plate 14, and the lower portion of the truck frame wheel piece.

Pedestals of my improved construction are 45 comparatively simple, can be easily and cheaply manufactured, are so constructed as to facilitate machining and finishing of their wear receiving surfaces, and by forming the horns or jaws of the pedestals separate, a material saving in the cost and labor 50 of repairs is effected.

It will be readily understood that minor changes in the size, form and construction of the various parts of my improved pedestal can be made and substituted for those 55 herein shown and described, without departing from the spirit of my invention, the

scope of which is set forth in the appended claims.

I claim:

1. As a new article of manufacture, a pedestal jaw comprising a pair of vertically disposed integrally connected plates, the inner edges of which are provided with hardened surfaces. 65

2. As a new article of manufacture, a pedestal jaw comprising a pair of integrally connected plates, bearing ribs on the inner edges of said plates, and the inner edges of said plates and said bearing ribs being 70 provided with hardened surfaces.

3. A pedestal for car trucks comprising a pair of separate jaws, each formed in a single piece, and each jaw being provided on its inner face with a hardened wear receiving surface. 75

4. A pedestal for car trucks comprising a pair of separately formed jaws, and each jaw comprising a pair of vertically disposed integrally connected plates having hardened wear receiving surfaces which are adapted to be engaged by the journal boxes 80 positioned between said jaws.

5. A pedestal for car trucks comprising a pair of separately formed jaws, and each jaw comprising a pair of vertically disposed integrally connected plates, and the inner edges of said plates being provided with hardened surfaces. 85

6. A pedestal for car trucks comprising a pair of separately formed jaws, and each jaw comprising a pair of vertically disposed integrally connected plates, ribs on the inner edges of said plates, and the inner edges of said plates and ribs being provided 90 with hardened surfaces. 95

7. As a new article of manufacture, a pedestal jaw comprising a pair of vertically disposed integrally connected plates, the inner edges of which are provided with finished hardened surfaces. 100

8. As a new article of manufacture, a pedestal jaw comprising a pair of integrally connected plates, bearing ribs on the inner edges of said plates, and the inner edges of 105 said plates and said bearing ribs being provided with finished hardened surfaces.

In testimony whereof I hereunto affix my signature in the presence of two witnesses, this 17th day of June, 1914.

HARRY M. PFLAGER.
